US00D988882S

(12) **United States Design Patent** (10) Patent No.: **US D988,882 S**
(45) Date of Patent: **** Jun. 13, 2023**

(54) **SENSOR ASSEMBLY**

(71) Applicant: **INFORMED DATA SYSTEMS INC.**,

New York, NY (US)

(72) Inventors: **Matthew Chapman**, Oakland, CA (US); **Steven Portela**, San Francisco, CA (US); **Ashwin Pushpala**, San Francisco, CA (US); **Mark Prommel**, Montclair, NJ (US); **Pil Ho Chung**, Palisades Park, NJ (US)

(73) Assignee: **INFORMED DATA SYSTEMS INC.**, New York, NY (US)

(**) Term: **15 Years**

(21) Appl. No.: **29/779,909**

(22) Filed: **Apr. 21, 2021**

(51) LOC (14) Cl. **10-04**

(57) **CLAIM**

The ornamental design for a sensor assembly, as shown and described.

DESCRIPTION

FIG. 1 is a top perspective view of a sensor assembly showing the new design.

FIG. 2 is a left side view of the sensor assembly in FIG. 1.

FIG. 3 is a right side view of the sensor assembly in FIG. 1.

FIG. 4 is a back view of the sensor assembly in FIG. 1.

FIG. 5 is a front view of the sensor assembly in FIG. 1.

FIG. 6 is a top view of the sensor assembly in FIG. 1.

FIG. 7 is a bottom view of the sensor assembly in FIG. 1; and,

FIG. 8 is a bottom perspective view of the sensor assembly in FIG. 1.

The details shown in broken lines illustrate portions of the sensor assembly that form no part of the claimed design. The dash-dot-dash broken lines illustrate the boundaries of the sensor assembly and form no part of the claimed design.
